UNITED STATES PATENT OFFICE.

GUSTAV SPINDLER, OF SAN FRANCISCO, CALIFORNIA.

DESIGN FOR A MICROSCOPICAL LAMP.

Application filed May 31, 1928. Serial No. 26,913. Term of patent 3½ years.

To all whom it may concern:

Be it known that I, GUSTAV SPINDLER, a citizen of the United States of America, residing at San Francisco, in the county of San Francisco and State of California, have invented a new, original, and ornamental Design for a Microscopical Lamp, of which the following is a specification, reference being had to the accompanying drawing, forming a part thereof.

Figure I is a side elevation of my design, and

Figure II is a rear elevation of the same.

I claim:—

The ornamental design for a microscopical lamp, substantially as shown.

GUSTAV SPINDLER.
